UNITED STATES PATENT OFFICE.

AUGUSTUS G. DAVIS, OF BALTIMORE, MARYLAND.

PORTABLE SUPPORT FOR TELEPHONES.

No. 799,722.

Specification of Letters Patent.

Patented Sept. 19, 1905.

Application filed January 5, 1905. Serial No. 239,703.

To all whom it may concern:

Be it known that I, AUGUSTUS G. DAVIS, a citizen of the United States, residing at Baltimore, in the State of Maryland, have invented certain new and useful Improvements 5 in Portable Supports for Telephones, of which the following is a specification.

My invention relates to improvements in portable telephones and supports therefor.

10 The object of the invention is to provide an improved support in the form of a flexible case to which the telephone apparatus is secured and which may be folded about the said apparatus to cover and protect it and 15 form a small compact package that may be carried in the pocket.

Another object of the invention is to provide a construction of case having flaps or sides which when the telephone apparatus is 20 in use out of doors will serve as shields to direct the sound of the voice into the transmitter and prevent the noise or currents of air from interfering.

The invention is useful in all cases where 25 portable telephones are employed. It is especially adapted for use in connection with street-railway and fire-alarm systems, where it often becomes necessary to establish a telephonic communication directly with head- 30 quarters to report trouble, or in case of fire departments to give orders that are to be executed promptly and without error, such as might occur through most any system of gong-signals used by fire departments.

35 I am aware that portable telephones and outfits are now in use, and my present invention has been especially designed to overcome serious objections to the present devices because of their bulky character, as well as the 40 inconvenience in getting them into operation. By my invention the telephone outfit is reduced in bulk and is capable of being readily placed in a coat-pocket and is also protected from damage in case it be accidentally dropped or knocked against something, as is liable to 45 occur.

While the accompanying drawings illustrate the invention in connection with a fire-alarm box, it is to be understood that this is 50 merely illustrative and that the invention may be employed in various kinds of service.

In the drawings, Figure 1 illustrates a perspective view of a fire-alarm box opened and with my improved portable telephone outfit 55 attached to the door of the box and showing

the connection made ready for use. Fig. 2 illustrates a side view of the opened case with the wall of the receiver-receptacle in section with the receiver in position. Fig. 3 shows a perspective view of the folded case containing the telephone; and Fig. 4 is a top plan view of the transmitter, showing the flaps of the case in position to serve as side shields when the telephone is in use.

In the drawings, 1 designates the center or 65 foundation plate of the portable support, which is provided with opposite side flaps 2 and 3 and end or top and bottom flaps 4 and 5. These side and end flaps are all flexibly connected to the center plate and are prefer- 70 ably made of soft flexible leather or canvas, so as to permit of drawing closely about the inclosed apparatus and also to serve as a cushion and protection for the latter. The side flaps 2 and 3 also perform a useful func- 75 tion during the operation of talking by serv- 80 ing as shields or walls at opposite sides of the transmitter to prevent the escape of the sound of the voice while talking when the apparatus is in use out of doors where there is noise and wind, as will hereinafter be more fully described.

A transmitter 6 of any preferred form is rigidly secured in a circular receptacle 7, 85 fixed on the inner side of the base or foundation plate 1 and between the two opposite side flaps 2 and 3, and flexible cord conductors 8 extend from the transmitter and carry a plug connection 9 at their ends. Cord conductors 10 are also connected through the 90 transmitter to the conductors 8, and said conductors 10 are electrically connected with a receiver 11. A receptacle 12 is also rigidly attached to the foundation-plate 1 and is shaped to correspond with the exterior form 95 of the receiver 11, so that the latter when not in use may be fitted into said receptacle 12 and there held.

The end flap 4, which is the top flap, is provided adjacent its edge with hook-plates 13, 100 which are preferably riveted to the inner surface. The hooks extend over the edge of the flap and are bent back toward the base-plate on the exterior surface of the flap. A clip 15 is also secured to the edge of the end flap 4 105 between the hook-plates 13, and said clip carries a ring 16 for a purpose to be presently described. The end flap 5, which is the bottom flap, is provided on its outer surface with a hook 17, which when the end flaps are folded 110

over the transmitter and receiver may be made to engage the ring 16 on the flap 4, and thereby hold the two end flaps in the folded position. The side flaps 2 and 3 are also provided with 5 engaging devices 18, which serve to hold them together when they are folded over the end flaps, as seen in Fig. 3.

As one example of the device in practical operation I will proceed to describe the same 10 when used in connection with a fire-alarm telegraph system. In such use one of these portable telephone equipments will be supplied for the proper officers in the department, so that any of them may, either on the way to a 15 fire or after reaching the fire-ground, quickly unfold and attach his telephone apparatus to a fire-alarm box and immediately get into communication with headquarters. In making connection with a fire-alarm box the side flaps 20 4 and 5 are disengaged. This can be done quickly while approaching the box 19, which is ordinarily attached to a post 20. The outer door 21 of the box is then opened, as is also the inner door 22, which is swung back. The 25 exterior hooks 14 on the end flap 4 are then placed over the upper edge of the inner door 22, as seen in Fig. 1. The plug connection 9 when inserted in the plug-block 23 puts the telephone in operative condition, and the signal-key 24 may then be operated to call "headquarters." It will thus be seen that the telephone is suspended by one of the flexible end flaps, while the broader side flaps 2 3 are free and may be swung to a position at right angles 30 with the base 1, as in Fig. 4, so as to project at each side of the operator's face and form side shields to direct the sound of the voice into the transmitter, and thus assist in conducting a conversation with ease even on a 35 noisy thoroughfare.

In street-railway service the plug-blocks 23 may be located at convenient intervals along the line, and, if desired, the apparatus may be held in the hand during the talking operation, 40 as the side shields will perform their func-

tions whether the case is suspended or merely held in the hand.

It is to be understood that the construction of the telephone apparatus is immaterial and may be altered to suit the requirements of the 50 particular service in which the same is to be employed.

Having thus fully described my invention, what I claim as new, and desire to secure by Letters Patent, is—

55

1. A support for portable telephone apparatus comprising a base having flaps projecting from opposite sides of said base; a transmitter secured to the base between the said flaps whereby the flaps may be folded over and 60 cover said transmitter; a receiver; means on the base for holding the receiver to the base between said flaps, and wire connections for the receiver and transmitter.

2. A support for portable telephone apparatus comprising a base with side flaps connected to and foldable toward each other over said base and also having an end flap extending at right angles with respect to and between said first-named flaps and also foldable over 70 said base, in combination with a transmitter secured to said base between said flaps, engaging devices on said end flap which serve to hang up the apparatus, a receiver and connections for the receiver and transmitter.

75

3. A support for portable telephone apparatus comprising a base and flexible side and also end flaps which are foldable over said base, in combination with a transmitter secured to said base between said side and end 80 flaps, means on one of said flexible flaps by which the apparatus may be hung, a receiver and wire connections for the receiver and transmitter.

In testimony whereof I affix my signature in 85 presence of two witnesses.

AUGUSTUS G. DAVIS.
